UNITED STATES PATENT OFFICE.

CARL LOTT, OF HORGEN, SWITZERLAND.

DEVICE FOR DRIVING SHAFTS AT A LOW AND UNIFORM SPEED BY AN ELECTRO-MOTOR.

Application filed June 15, 1922. Serial No. 568,538.

To all whom it may concern:

Be it known that I, CARL LOTT, a citizen of the Swiss Confederation, residing at Bergstrasse Horgen, Canton Zurich, Switzerland, have invented new and useful Improvements in Devices for Driving Shafts at a Low and Uniform Speed by an Electromotor, of which the following is a specification.

10 In connection with the electric driving of slowly running shafts, particularly in the driving of record disc tables of talking machines, a series of requirements cannot be fulfilled by the means hitherto employed.

15 A record disk has to run at an uniform speed over a long time and for every single revolution, which is difficult to obtain as the low speed of the disk prevents the use of the momentum of the rotating disk table 20 as a speed regulator.

The speed of the shafts should be independent of the variations of potential; of the changes of temperature; of the surroundings, as well as of the heating of the 25 windings and of variations in the magnetic quality or behaviour of the iron of the electric motor. Finally absolute noiselessness and freedom of the record disc from vibrations, which would cause noises in the 30 sound box is required.

The quick running motors hitherto employed, which work with transmission gear on the record disc shaft, have some or all of the faults indicated.

35 According to this invention slowly rotating shafts and particularly record disc shafts are driven direct and slowly by an electric motor without intermediate gear, the stator field or the rotor field or both 40 fields of the motor being supersaturated.

The motor has a great internal resistance which consumes the greater part of the voltage. I use preferably series motors which might be used with continuous or 45 alternating current but shunt motors may be used to obviate the faults mentioned. By supersaturation I wish to denote an iron having a density of lines of force of 20000 and more Gauss. By this high magnetizing

50 I obtain the condition that variations of the exciting current in wide limits do not pro-

duce any considerable variations of the field and practically no variations of the torque. Owing to the supersaturation and the high internal resistance the current consumed by the motor is quite independent of the speed of rotation and remains constant not only at any speed but even when the motor is at rest. In alternating current motors the reactance of the windings is 55 added to the internal ohmic resistance.

As according to this invention, the internal resistance is great, in order to lessen the influence of the variations of potential on the number of revolutions the degree of 60 efficiency is rather low but other advantages are gained as aforesaid.

The supersaturation of the field need not affect the whole magnetic circuit. It is sufficient if it exists at a suitable part of 65 the magnetic circuit, in the stator or the rotor, or both.

In the drawings an electric motor for driving the record disc of a talking machine is shown in a diagrammatical manner. *m* is the motor, *f* is the supersaturated iron yoke, *n* is the shaft and *e* the record disc table whilst *r* represents the centrifugal regulator, which can be adjusted by means of a lever *h* to effect more or less braking 70 effect, whereby the speed of the sound disc is regulated.

Having now particularly described and ascertained the nature of the invention, and in what manner the same is to be performed 75 I declare that what I claim is:

Electric device for direct driving of shafts at low and uniform speeds, comprising an electromotor with its armature mounted upon said shaft and a centrifugal 80 brake governor for said electromotor, and in which the magnetic field of the electromotor is supersaturated to a density of 85 lines of force of 20000 and over per cm.², substantially as and for the purpose set 90 forth.

In witness whereof I affix my signature.

CARL LOTT.
